MECHANICAL TOY

Herman G. Fisher, East Aurora, N. Y., assignor
to Fisher-Price Toys, Inc., East Aurora, N. Y.

Application May 29, 1936, Serial No. 82,538

7 Claims. (Cl. 46—98)

This invention relates to mechanical toys and it has particular relation to toys having movable parts which operate as a result of rolling the toy along the floor or some other surface.

5 One of the objects of the invention is to provide an improved toy of this character embodying a simplified mechanism for motivating a plurality of movable elements in different planes of motion.

10 Another object is to provide a toy which has movable limbs wherein an axle is provided with means connected to the limbs for translating rotational motion of the axle into straight line reciprocation and rotative oscillation to move the 15 limbs in transverse planes.

One embodiment of the invention is exemplified in a toy which includes front and rear supporting axles and pairs of wheels secured thereto. One of the pairs of wheels is fixed in rigid relation to one of the axles, and the latter is provided with angular or bent portions to which actuating members are connected in such manner that limbs or other members of the toy can be connected thereto for oscillation in different 20 planes as the toy is rolled along the floor, or other support, and in response to operation of the angular portions of the rotating axle. One of the actuating members is pivotally connected to an inclined angular portion of the driving 25 axle, and this portion, in response to rotation of the axle, describes a somewhat conical path of motion for the purpose of imparting to the actuating member a partially rotative or oscillatory motion about its longitudinal axis. The 30 other actuating member is connected to a portion of the axle that forms a substantially crank-like arrangement, and hence, rotation of the axle causes this member to be operated, or reciprocated at its outer end, in a manner similar to 35 the operation of a pitman.

In the drawing:

Fig. 1 is a perspective view of a toy in which the invention has been incorporated;

Fig. 2 is a perspective, on a larger scale, of the 45 working elements of the toy;

Fig. 3 is a fragmentary bottom plan showing details of the toy construction;

Fig. 4 is a fragmentary view on a larger scale, showing in detail a connection for one of the 50 operating elements of the toy; and

Fig. 5 is a fragmentary view showing in detail a motion translating connection employed in the toy construction.

In practicing the invention, a platform or 55 frame 10 is provided which can be formed of

wood, or other suitable material, and is provided with depending flanges 12 having bearing members 13 that can be in the form of staples or similar elements. A transverse axle 15 having wheels 16 rigidly secured to opposite ends thereof is rotatably supported in the bearing members 13. Another similar pair of wheels 17 mounted upon an axle 18 that is carried in the frame 10, supports one end of the frame opposite the wheels 16.

An intermediate portion of the axle 15 is provided with an integral offset section 20 parallel to the axis of rotation of the wheels and which is joined with the body of the axle by means of an inclined section 22 and a substantially radial section 23. An upright actuating member 25, which can be in the form of a wire, is provided at its lower end portion with an eye or loop 26 embracing the horizontal section 20 in rotatable or pivotal relation, and this actuating member extends upwardly through a guiding slot 27 formed longitudinally in the frame 10. The upper end of the actuating member is bent to form a finger 28 that is pivotally connected, as indicated at 29, to an intermediate portion of a limb 30 of a toy figure 32. This figure is rigidly supported upon the frame 10. One end portion of the limb 30 is provided with a pivotal connection 33 securing it to the toy figure 32, and the other end portion of the limb 30 is provided with a striking element 35, which can be in the form of a toy cymbal, for striking a similar element or cymbal 36 that is mounted upon a toy sounding member 37 shown in this embodiment of the invention as being a toy drum. The frame 10 is provided with a block support 38 formed thereon upon which the drum 37 is rigidly mounted.

A second actuating member 40 is bent or formed at its lower end with a hooked portion 42 defining an elongate bearing loop or slot 43 in which the inclined section 22 of the axle is relatively loosely disposed. This actuating member 40 can be in the form of a wire or similar element and extends upwardly through a guiding slot 45 formed longitudinally in the frame 10 and substantially parallel to the slot 27. It will be noted that the slot 45 registers substantially with an intermediate portion of the inclined section 22 and that the actuating member 40 can move in the slot longitudinally of the frame 10 and the slot serves as a guide to prevent lateral movement of the actuating member from direct engagement with the inclined section of the axle. The upper end portion of the actuating mem- 55

ber 40 extends through a bearing member 47, which can be in the form of a staple secured in the toy figure 32 opposite the pivotal connection 33 of the arm 30, and just beyond the bearing 5 member 47 the actuating member is formed with an angular finger 48 that is rigidly secured to an end portion of a limb 50 similar to the limb 30. The outer end of the limb 50 is provided with a striking element 52, which can be in the form of a 10 toy drum stick and is adapted to strike the drum 37 during lateral movement of the limb 50.

When the toy is rolled along a support or floor upon the wheels 16 and 17 the axle 15 is rotated and operates the actuating members 25 15 and 40. The section 20 of the axle 15 serves as a crank to reciprocate the actuating member 25 and thus to impart an upward and downward oscillating motion to the end of the limb 30 about its pivotal connection 33 to strike the cymbals.

20 At the same time, the actuating member 40 is rotated about its longitudinal axis as a result of oscillatory camming action imparted by the inclined axle section 22 to the loop 42 or slotted portion thereof, while the lower end portion of the 25 actuating member is guided to and fro in the slot 45 (Fig. 3) of the toy frame 10. Rotative movements in the form of oscillatory impulses are thus imparted to the actuating member 40 and are translated into lateral beating action of the 30 striking element 52 for beating the drum.

The portion of the inclined section 22 that engages the loop 42 describes an annular or conical path as the axle 15 rotates, and the relative variation in position of the engaging portions of 35 the loop and inclined section is compensated by the elongate configuration of the loop. The branches of the loop carried by the rod 40 are so positioned that the forward portion is caused to turn with relation to the rear portion, when the 40 inclined section 22 of the axle, positioned therebetween, is turned by movement of the wheel. This turning movement of the forward branch of 45 the loop is simultaneous with the lateral shifting of the rod 40. That is, the lower part of the element 40 is moved laterally and concurrently oscillated about its longitudinal axis, but is not actuated longitudinally because of the shape of the bearing loop 43, and the slot 45 prevents loop 43 from being displaced from proper association 50 with the inclined section 22. It is to be understood that the lateral movement of the lower portion of the member 40 is longitudinal with reference to the slot 45. It will be noted that the diameter of the annular path of the inclined section 22 at the location of engagement 55 with the loop 42, is relatively small as compared with the distance from the loop 42 to the pivotal connection 47, and hence, the principal and major phase of movement of the limb 50 is in 60 lateral directions about the pivotal connection 47. At the same time, there is slight pivoting of the limb 50 upwardly and downwardly as a result of movement of the loop 42 with the inclined section 22. The ratio of the lateral drum striking 65 motion to the upward and downward motion of the striking element 52 is greater than 5 to 1. The upward motion commences approximately at the time the element 52 strikes the drum, or just prior to this time. It is to be understood 70 that the manner of connection of the actuating member 40 to the inclined section of the axle can be altered to vary the ratio mentioned as well as to vary the degree of upward or downward motion occurring in the limb 50 at 75 the location of the striking element 52.

When the loop 42 is in the position shown in full lines of Fig. 3, the element 52 is striking or is adjacent the drum and such element is also in its lower position. On the other hand, when the loop 42 is in the position indicated by broken 5 lines of Fig. 3, the element 52 has been moved laterally away from the drum and to its higher location. As viewed in Fig. 4, it will be observed that the staple 47 is in an inclined position and that the bent portion 48 of the actuating member 10 rides upwardly and downwardly upon this inclined staple 47 as the limb 50 is actuated laterally in drum beating action. When the element 52 is in its higher position away from the drum and then travels slightly downwardly to striking 15 position, the fact that the staple 47 is inclined and the further fact that the force of gravity has certain influence upon the element 52, provide for added impetus to the drum beating stroke of the limb 50.

20 Since the elongate loop 42 fits loosely about the inclined section 22, there is appreciable play in the connection and after the camming action of the loop generates momentum in the limb 50 in its outward swinging motion, this limb continues 25 outward movement until the space for play provided in the loop is traversed. The slot 45 prevents the loop from being displaced materially toward or away from the axis of wheel rotation along the section 22. Thus free and sharply defined beating action is achieved by translation of the motion of a uniformly rotating axle, and by employing a minimum number of parts.

30 Although only one form of the invention has been shown and described in detail, it will be 35 apparent to those skilled in the art that the invention is not so limited but that various changes can be made therein without departing from the spirit of the invention or from the scope of the appended claims.

40 I claim:

1. A toy comprising a support, a figure having a movable limb and carried on said support, means for pivotally connecting the limb to the figure, an axle and wheel unit rotatably carried 45 in the support, said axle having a section inclined with respect to the axis of rotation of the axle, an actuating member formed with an elongate opening through which the inclined section of the axle is loosely disposed, means in the support 50 for maintaining the actuating member against lateral displacement from the inclined section of the axle, said actuating member having a connection to the movable limb whereby rotation of the axle imparts an oscillatory action to the actuating member and operates the limb in substantially a predetermined plane of oscillation.

2. A toy comprising a support, a figure having 55 movable limbs and being carried by the support, means for pivotally connecting the limbs to the figure, axle and wheel structure connected to the support, a portion of the axle structure being offset to provide a crank-like arrangement, an actuating member articulated to the crank-like arrangement and to one of the movable limbs for actuating the latter in substantially a predetermined plane, said axle structure having an inclined section, a second actuating member articulated to said inclined section and connected to the other of the movable limbs for actuating the latter substantially in a plane at approximately right angles to the plane of operation of the first actuating member.

3. A toy comprising a support, a figure having 60 a pair of movable limbs and being carried by the 65

support, means for pivotally connecting the limbs to the figure, a pair of wheels having an axle rigidly secured thereto and rotatably carried in the support, said axle having a section bent and offset to provide a crank-like arrangement, an elongate actuating member having one end looped about the crank-like arrangement of the axle, the other end portion of the actuating member being pivotally connected to one of the limbs of the figure to oscillate the latter limb in a predetermined plane, said axle having a section inclined with respect to the axis of rotation of the axle, a second elongate actuating member having an oblong loop formed in one end portion and having said loop engaging loosely about the inclined section of the axle, means in the support for maintaining the loop against lateral displacement from the inclined section, said second actuating member having a connection directly to the other limb adjacent its pivotal connection to the figure whereby movement of the second actuating member in response to operation of the inclined section of the shaft in said loop imparts oscillatory movement to the latter limb in a plane of oscillation approximately at right angles to the plane of oscillation of the limb actuated by the first actuating member.

4. A toy comprising a support, a wheel having an axle rigidly secured thereto and rotatably carried in said support, said axle having a section inclined with respect to the axis of rotation of the axle, a movable member including an actuating element formed with an opening through which an intermediate portion of the inclined section of the axle is disposed, means carried by said support and pivotally anchoring a portion of said actuating element remote from the axle connection thereof, said actuating element extending to said movable member and connected thereto whereby rotation of the axle imparts os-

cillatory movement to said member and element.

5. A toy comprising a figured support having a limb with a downwardly extending actuating part, means mounting the limb for lateral oscillation about the axis of said downwardly extending actuating part, and a wheel having a rotating axle rigidly secured thereto and supporting the figured support, said axle having a section inclined with respect to the axis of rotation and bodily movable about such axis of rotation, said downwardly extending actuating part having spaced portions straddling the inclined section. 5

6. A toy comprising a figured support having a limb with a downwardly extending actuating part, means mounting the limb for lateral oscillation, and a wheel having a rotating axle rigidly secured thereto and movably supporting the figured support, said axle having a section inclined with respect to the axis of rotation and bodily movable about such axis of rotation, said 10 downwardly extending actuating part having spaced portions straddling the inclined section, and means for constraining the actuating part against movement axially of the axle. 15

7. A toy comprising a figured support having a limb with a downwardly extending actuating part, means mounting the limb for lateral oscillation about the axis of said downwardly extending actuating part, and a rotatable wheel having an axle rigidly secured thereto, said axle having a 20 section inclined with respect to the axis of rotation and bodily movable about such axis of rotation, said downwardly extending actuating part having spaced portions straddling the inclined section, the sectional dimension of the inclined 25 section of the axle being materially less than the space between the spaced straddling portions to provide a lost motion connection between the axle and said actuating part. 30
